PUMP OR ENGINE

Samuel Barton Brown, Los Angeles, Calif.

Application November 19, 1932, Serial No. 643,382

2 Claims. (Cl. 103—144)

This invention relates to pumps or engines and more particularly to a device which may be used as either a pump or an engine.

The primary object of this invention is to provide a pump and engine of the rotary type which may be used as a blower or as a pump for pumping fluids of all kinds, gaseous or liquid, and which may be used equally well as an engine adapted to be driven by steam or any kind of gas 10 or liquid which is under suitable pressure.

A further object is to provide a pump and engine of the character described which is simple in construction, durable, and exceptionally efficient in its operation.

Other objects will appear hereinafter as the details of the invention are described.

Referring to the accompanying drawing which illustrates what is at present deemed to be a preferred embodiment of the invention,

Fig. 1 is a longitudinal sectional view taken approximately in a vertical plane through the axis of the device, as on line 1—1 of Figs. 2 and 3.

Fig. 2 is a transverse sectional view of the pump and engine shown in Fig. 1, taken on line 2—2 of Fig. 1.

Fig. 3 is a reduced end-view of the device, as seen when looking in the direction indicated by arrow 4 in Fig. 1.

Fig. 4 is a fragmental sectional view taken on line 4—4 of Fig. 1.

As clearly shown in Figs. 1 and 2, the pump and engine comprises an outer shell or casing 10, made up of a cylindrical middle section 11, a front end section 12, and a rear end section 13 having an end plate 14 attached thereto, and an inner rotary member 15 made up of a cylindrical section 16, of considerably smaller diameter than of section 11 of the casing, and a front end section 17 having a shaft 18 extending from the center thereof which is made integral therewith. End sections 12 and 13 of the casing have cylindrical portions 12a and 13a respectively, whose common axis is in offset relation to the axis of middle section 11. The internal diameter of said cylindrical portions 12a and 13a corresponds to the external diameter of rotor 15, so that the ends of the latter are adapted to turn in the former. External flanges 12b and 13b of varying width, between which middle section 11 is clamped by bolts, studs or cap screws 19 extending through them are formed on the cylindrical portions 12a and 13a respectively, of end sections 12 and 13. Front section 12 is provided with a bearing flange 12c in which shaft

18 is adapted to turn, as presently will appear, and rear section 13 is provided with a second external flange 13c against which end plate 14 is held by cap screws 20 the ends of which are seated in said flange 13c.

Middle section 11, of the casing, is formed of a cylindrical metal ring 21, of relatively large diameter, having comparatively thick walls 21a and heavy external flanges 21b at each end thereof and a wide metal band 22, fitting closely between flanges 12b and 13b, said band being clamped against flanges 21b, by bolts 23 which extend through lugs 24 fixed adjacent the ends of the band. An annular space 25 is thus formed between said band 22 and wall 21a or ring 21. Two pipe fixtures 26 and 27, equally spaced from a vertical plane through the axis of the casing, are attached to band 22 and suitable openings 22a are made therein to permit communication between said pipe fixtures and annular space 25.

A tightly fitting block 28 is fixed in middle section 11, midway between pipe fixtures 26 and 27, so as to obstruct direct communication therebetween through annular space 25. Similar but movable obstruction blocks 29 and 30, adapted to be held in adjusted positions by machine bolts 31 which are movable in slots 22b cut in band 22, are mounted in annular space 25 in spaced relation to block 28 and in diametrically opposite positions from each other. Closure plates 32 adapted to keep slots 22b closed, are fitted under the heads of bolts 31.

Two separate portions of annular space 25 are thus cut off to form chambers 25a and 25b which communicate with pipe fixtures 26 and 27 respectively. A series of parallel slots 33 are cut through that portion of wall 21a which is coextensive with chamber 25a and another series of similar slots 34 are cut through that part of wall 21a which is coextensive with chamber 25b thus forming a path of communication from one chamber to the other through the interior of middle section 11 of the casing.

Cylindrical section 16 of rotor 15 is provided with internal flanges 16a and 16b on its front and rear ends, respectively, and with a series of equally spaced longitudinal bearings 16c where ends terminate in said flanges 16a and 16b. Diametrically opposite slots 35 and 36 are formed longitudinally in bearings 16c in planes radiating from the center of the rotor. The end section 17 of rotor 15 is held rigidly attached to the cylindrical section 16 thereof by 55

cap screws 37 whose ends screw into flange 16a of the latter.

As shown in Fig. 1 the rear end of rotor 15 is preferably equipped with ball bearings 38 and 5 the front end with roller bearings 39, the fixed ring 38a of the ball bearing being seated on a central boss 14a formed on rear plate 14, so as to project within the rear end of rotor 15, and the turning ring 38b being clamped between 10 flange 16b of the rotor and a ring 40 held in contact therewith by cap screws 41. Fixed ring 38a is held securely seated on boss 14a by a circular plate 42 which is held in place by a stud bolt 43.

15 Fixed ring 39a of the roller bearing is held seated in flange 12c of the casing by an extension ring 44 butting against flange 12c and in a clamping ring 45 fitting within flange 12c. A retaining washer or shim 46 is placed between 20 clamping ring 45 and bearing ring 39a and these several parts are held in place by machine bolts 47, the ends of which screw into clamping ring 45. Turning ring 39b of the roller bearing is held on shaft 18 against a spacing sleeve 48, which is slipped on the shaft, by a clamping nut 49 working on a threaded portion of the 25 shaft.

Portions of both extension ring 44 and clamping ring 45 are bored out so as to form suitable 30 seats for packing rings 50 and 51.

From the construction thus far described and by reference to Fig. 2 it will be seen that, due to the difference in diameter of the rotor and the middle section of the casing and to the eccentric 35 position of the former in the latter, the space between the former and the inner wall of the latter is not of uniform depth. While the upper side of the rotor is in actual contact with the inner wall of the casing, as shown, there is a 40 space S between them which increases uniformly from the upper part to the lower part of the casing.

A tubular shaft 52 extending through plate 42 and boss 14a is fixed in end plate 14 of casing 45 so that its axis coincides with the axis of the middle section 11 of the casing and its free end projects forwardly within rotor 15, a distance approximately coextensive with the cylindrical section 16 thereof. A circular plate 53 is held in 50 contact with the free end of tubular shaft 52 by a stud bolt 54 which extends axially through tubular shaft 52 and has a large washer 55 on its outer end which contacts with the outer 55 face of plate 14. A turnable sleeve 56, having a flange 56a on one end in contact with plate 53 and its other end butting against plate 42, is slipped on tubular shaft 52 and a spacing washer 57 is fitted tightly on this other end of the sleeve. Two relatively large and heavy discs 60 and 59, one in contact with flange 56a and the other with washer 57, are fixed on sleeve 56 so as to turn therewith.

A series of equally-spaced straight blades 60a, 60b, 60c, 60d and 60e extending radially within 65 middle section 11 of the casing and having their outer ends in contact with the inner wall 21a thereof, pass through slots 35 and 36 of bearings 16c and also through suitably slotted pins 61 which are adapted to turn in said bearings 16c. The dimensions of the slots in pins 61 correspond closely to the width and thickness of the blades which pass through them but they are sufficiently large to permit free longitudinal 70 movement of the blades therein. As shown in Fig. 2 slots 35 and 36 are made wide enough to

provide ample clearance for the blades in whatever position they may be with reference to rotor 15.

It should be understood that the width of the blades is such as to span the space S in the lower part of the casing and at the same time to permit their movement therein without undue friction. One of the blades, 60a as here shown is made slightly wider on its inner end and is welded or otherwise rigidly secured to 10 discs 58 and 59. The inner ends of the other blades 60b, 60c and 60d and 60e are held in place by heart-shaped discs 62b, 62c, 62d and 62e having deep notches cut therein, as shown in Fig. 2, in which the blade ends are seated. 15 These heart-shaped discs are fixed, in suitably spaced pairs to accommodate the different blades, on sleeve 56.

From the construction shown and described it is evident that when either the rotor or the 20 blade assembly which forms a floating vane structure, is caused to rotate in either direction it will cause the other to rotate therewith. For instance, if power is applied to shaft 18 so as to cause rotor 15 to turn in the direction 25 indicated by the arrow in Fig. 2, the blade assembly will be driven in the same direction and the outer ends of the several blades will sweep through space S thus causing fluid to be drawn into the casing pipe fixture 27 and slots 34 and 30 to be driven out again through slots 33 and pipe fixture 26. This is the action which takes place when the device is used as a blower or a pump. On the other hand if the device is to be used as an engine suitable connections are made to 35 shaft 18 and steam, gas or liquid under suitable pressure is admitted into pipe fixture 27. The pressure exerted thereby on the several blades as it travels through space S on its way through 40 the device, obviously, will cause the blade assembly to rotate and drive the rotor and shaft 18.

The purpose of obstruction blocks 29 and 30 is, as readily may be seen, to cover some of the 45 slots 33 and 34 and thus reduce or vary the inlet and outlet capacity of the pump and engine.

While the device here shown has five blades it is understood that similar machines having a greater or smaller number of blades may be 50 constructed and other minor changes may be made without departing from the spirit of the invention.

The bushing 56 and end washer 57 are pinned to end washers 58 and 59 so the whole mass including blade 60a rotate as a unit on spindle 52. The remaining four blades 60b, 60c, 60d and 60e rotate with bushing 56 but are free to oscillate relatively back and forth in angular relation to each other. When said blades are at the top of the pump or engine they are angularly closer together than when at the bottom. The blades 60a, 60b, 60c, 60d and 60e are arranged to rotate with the bushing 56 to 65 balance the wear due to centrifugal force on spindle 52 and also to minimize the wear between bushing 56 and parts 62b, 62c, 62d and 62e. The fixed relation of the blade 60a to the remainder of the rotating structure strengthens and stabilizes the operating parts.

The inner ends of blades 60b, 60c, 60d and 60e are widened out to touch circular pieces 58 and 59 which in turn are restricted end ways with bushing 56a and 57 ends, to restrict the endwise movement of the blades and give proper clear- 70 75

ance between them and the crescent shaped walls of core parts 12b and 13b.

The blades 60a, 60b, 60c, 60d and 60e are arranged to rotate on the spindle 52 through bushing 56 but restricted from touching the inner surface of the case 21a, said blades being fitted to prevent leakage with a slight running clearance, but not actually touching to prevent undue friction and wear at this point.

10 When used as a pump or blower the rotor turns clockwise (see arrow) so as to draw in fluid through parts 34, at receiver pressure. The fluid or gas is then compressed between the 15 rotor and case between said blades before being ejected through ports 33 to receive pressure.

15 By varying the angular exit openings at 33 to suit the receiver pressure a reversal of flow of the fluid or gas through these ports 33 can be diminished or entirely prevented.

20 When used as a motor, the rotor turns anti-clockwise and by varying the angular openings of 33 the cut-off can be regulated so as to take advantage of the expansion of gases traveling therethrough.

25 Fig. 4 illustrates more clearly one of the seats or recesses 61a formed between one of the pins 61 and the front end section 17 of the rotor. The recesses 61a aid in shutting off pressure leakage from chamber S through the annular 30 recess 17x to the center portion of the rotor assembly. The lip portion 17z which surrounds the annular recess 17x, and which has in it the curved seats 61a, is sufficiently thick to compensate for the formation of said seats therein.

35 The depth of each seat 61a is considerably less than its width. As indicated by the sectional view (Fig. 4) taken on line 4—4 of the lower portion of Fig. 1, the recesses which form these seats are located near one side of the end section 17 of the rotatable member and in a plane at which it is necessary to supply some special means where the running fit occurs to prevent pressure leakage from the crescent-shaped chamber S to the space within the rotor assembly.

45 Owing to the fact that the lip 17z is imperforate opposite to each shallow concavity or seat 61a leakage is prevented where the running fit occurs. Said concavities may be quickly and 50 easily made by the use of a suitable rotary cutter.

The curved seats 61a extend over relatively small segments of the end portions of the pins 61 and constitute parts of the bearing surfaces 55 and leak preventing means for the parts of the pins opposite to them. The result of this construction is that the bearing surfaces of said curved seats cooperate with bearing surfaces of the bearing elements 16c. Furthermore, said 60 seats 61a are formed in the end section 17 of

the rotor which is attached by the cap screws 37 to the cylindrical section 16 thereof. Therefore when long use causes said seats to become worn, the motor section 17 can be removed and replaced with an unworn part without discarding the entire structure of the rotor.

I claim:

1. In a rotary pump or engine of the type described, in combination, a casing; and a rotor mounted therein having an end section which is provided with an annular recess in the inner face thereof adjacent to its periphery, said rotor section being detachably secured to the remainder of the rotor and having a lip which surrounds said recess, there being a surface exterior to said lip with which it has a running fit and a series of curved seats formed in the inner side of said lip, said lip being imperforate opposite the outer sides of said seats to prevent leakage, a spindle, a plurality of rotor blades mounted upon said spindle, pins through which said rotor blades extend, and a cylindrical rotor section upon which said pins are mounted with a fluid-tight working fit, end portions of said pins being seated upon said curved seats to prevent leakage between the external and internal chambers of the structure, there being other bearing portions for said pins to cooperate with said curved seats, said other bearing portions being formed in the part of the rotor to which the aforementioned end section is detachably secured.

2. In a rotary pump or engine of the type described, in combination, a casing; and a rotor mounted therein having an end section which is provided with an annular recess in the inner face thereof adjacent to its periphery, said rotor section being detachably secured to the remainder of the rotor and having a lip which surrounds said recess, there being a surface exterior to said lip with which it has a running fit and a series of curved seats formed in the inner side of said lip, there being an imperforate portion of said lip opposite the outer side of each seat to prevent leakage, the depths of said seats being considerably less than their widths thereby providing shallow concavities, a spindle, a plurality of rotor blades mounted upon said spindle, pins through which said rotor blades extend, and a cylindrical rotor section upon which said pins are mounted with a fluid-tight working fit, end portions of said pins being seated upon said curved seats to prevent leakage between the external and internal chambers of the structure, there being other bearing portions for said pins to cooperate with said curved seats, said other bearing portions being formed in the part of the rotor to which the aforementioned end section is detachably secured.

SAMUEL BARTON BROWN. 60
